United States Patent Office.

G. A. WATKINS, OF PROCTORSVILLE, VERMONT.

Letters Patent No. 77,228, dated April 28, 1868; antedated April 6, 1868.

IMPROVED CHAIR-SEAT.

The Schedule referred to in these Letters Patent and making part of the same.

TO ALL WHOM IT MAY CONCERN:

Be it known that I, G. A. WATKINS, of Proctorsville, in the county of Windsor, and State of Vermont, have invented a new and useful Improvement on Chair and other Seats or Bottoms, of which the following is a full, clear, and exact description, reference being had to the accompanying drawing, forming part of this specification, and in which—

Figure 1 represents a top view of a chair-seat constructed according to my improvement,

Figure 2 a transverse section of the same through the line *s s* in fig. 1, and

Figure 3 a horizontal section thereof through the line *x x* in fig. 2.

Similar letters of reference indicate corresponding parts throughout the several figures.

This, my improvement, has reference to the manufacture of what are known as splint-chair and other seats, such as are made up of single thicknesses of strips woven together and secured at their ends to the frame, and my invention consists in a novel construction of the frame, and combination of parts for holding the splints at their ends, by cutting strips from the face side and along the outer edges of the frame, or the bars of which it is composed, so as to form a step-shaped recess or rabbet around the outer edge of the frame, and afterwards using the strips cut from the frame, in connection with an outside band or hoop, to hold the splints at their ends in a bent form corresponding to the rabbet, by which construction various advantages, as hereinafter set forth, are obtained.

Referring to the accompanying drawing, A represents the bars, or seat-frame which they compose, united at their ends, where they form a close angular joint, by keys, B, or otherwise suitably constructed. Around the outer edge of such or other frame, on the face-side of it, or the bars of which it is composed, I cut a rabbet, *a*, by, for each bar, two saw-cuts at right angles to each other, so as to form separate strips, C, the kerfs formed in making which give room for the ends of the splints D, when bent, and secured or held, by replacement of the strips C, over and on the interposed splint ends, to the places from which said strips were cut in the bars of the frame, and afterwards the whole held together by driving on an iron hoop or band, E, substantially as represented in fig. 2 of the drawing, said hoop being made either whole or divided, and of any suitable shape in its cross-section.

The splints D are preferably composed of one-grain or year's growth of tough wood of suitable width and thickness, and woven together, with their ends sufficiently projecting beyond the web to admit of their being bent into double-step form, and secured by crowding or pressing the strips C and hook E to their places. By this construction of seat the splints, it will be perceived, are most firmly secured at their ends without glue, or insertion of their ends in grooves more or less liable to be filled with dust, they being locked, not by an independent frame, but by the loose strips cut out of the one or main frame, which avoids waste of material, and the kerfs formed in making which allow for the thickness of the splints; so that on fitting to its place the outside band or hoop, E, a gripe or hold is formed on the splint-ends, both vertically and horizontally, which prevents all possibility of displacement without first taking off the hoop, that may, if desired, along with the strips C, be secured to the frame by screws. But these are not all or the most prominent advantages, as such a construction of the chair-seat is attendant with but little expense, while it affords the greatest security, not only as regards the holding of the splints, but by the general strength given to the frame through the hoop E, that serves the double purpose of securing, through the intervention of the strips C, the web or ends of the splints, and strengthening the seat generally. While by such construction all projecting cutting-edges are or may be avoided, the splints lie easy on or over the face of the frame, which prevents cutting at their end-lock or locks, and all exposure of their ends or junction of them to the frame is avoided, the construction giving a neat and finished aspect to the seat.

What is here claimed and desired to be secured by Letters Patent, is—

A chair or other seat or bottom constructed substantially as described, of a web of splints D, secured at their ends by means of a rabbet, *a*, made in and around the face of the frame A, in combination with the strips C, held to their places by a strengthening-band or hoop, E, essentially as specified.

G. A. WATKINS.
